SAFETY DEVICE FOR CONTAINERS FOR EXPLOSIVES, PARTICULARLY EXPLOSIVE GASES

Filed May 5, 1930

UNITED STATES PATENT OFFICE

HANS GROHMAN, OF HIRSCHFELDS, GERMANY

SAFETY DEVICE FOR CONTAINERS FOR EXPLOSIVES, PARTICULARLY EXPLOSIVE GASES

Application filed May 5, 1930, Serial No. 449,961, and in Germany July 24, 1929.

This invention relates to a safety device for containers charged with combustible (explosive) substances, so that in the event of an explosion occurring this shall not extend to 5 the inside of the container.

In the device according to this invention, there is interposed in the path of the combustible (explosive) substance or gas, a safety shield consisting of a quantity of some material such as sand, quartz, metal or other material of such consistency that the recoil caused by an explosion will compress the heap, so that firstly it acts as an obstacle, and secondly by absorbing and using up considerable quantities of heat in the form of mechanical energy, it prevents the propagation of the explosion.

It is desirable to select for the composition of the compressible heap, materials which 20 by undergoing physical or chemical changes can absorb still further quantities of heat.

According to the present invention, the heap is placed in front of the cross section of the pipe or vessel containing the explosive 25 substances that it is desired to protect, and it rests upon a plate perforated with small apertures and capable of resisting the bending strain caused by the high pressures due to an explosion, in such a manner that without 30 preventing the free passage under normal conditions of the combustible materials (gases), it will, in the event of an explosion, be mechanically compressed by the resulting shock, and will possibly also undergo a physical 35 or chemical change, with the result that the mechanical compression will either wholly or for the greater part close up the cross-section to be secured and prevent the gas from passing through it, whilst at the same 40 time a portion of the heat emitted by the explosion is absorbed in consequence of physical or chemical action upon the compressed heap. In this way not only is the container or pipe which it is desired to secure protected 45 against the shock of the explosion wave itself, but it is also protected against the heat which otherwise would be conveyed by conductivity.

The physical absorption of that part of 50 the heat of the explosion which is not ab-

sorbed by the work of deformation, may, for example be brought about in adequate degree by using as the filling substance a heap of particles of a metal in which the product of specific gravity, specific heat and heat conductivity is as large as possible, or alternatively by using a heap of particles of a substance that melts readily, for example, finely broken up sulphur, flour of sulphur, which under the action of the pressure caused by an explosion, whilst absorbing a certain amount of mechanical energy will become compressed, simultaneously beginning to fuse under the action of the heat of the explosion wave, thereby absorbing a large part of the explosion in the form of fusing heat. The absorption of a part of the explosion heat by means partly physical and partly chemical is also feasible by the choice of a suitable filling substance, for example, if we select ammonia alum, a salt containing up to 47% of water in the form of water of crystallization, with the result that the water in this substance is caused by the temperature of the explosion heat to evaporate, thereby absorbing a portion of the explosion heat. In the device forming the subject of this application, the heat is held as a result of the constitution of the filling substance forming the interposed heap, either by conduction, fusing, evaporation of moisture, or some other means, and partly by the simultaneous compression (deformation) of the filling substance itself. This compression absorbs heat by transforming it into mechanical energy and brings about at the same time a more intimate contact between the hot explosion gases and the filling substance, thereby reacting favourably upon the interchange of heat and finally closing up the passage against any further penetration of the explosion wave.

The accompanying drawing is partly an elevation and partly a vertical section of a container and provided with a safety device constructed and arranged in accordance with this invention.

In the embodiment of my invention here shown, a nipple N is screwed gas-tight into the container to be protected. This nipple 100

is provided with a screwed-on valve V and with the safety cartridge Q, consisting of a tube screwed on to the lower end of the nipple N, with a rigid perforated bottom P, 5 and filled with a heap of some suitable substance such as aluminium filings, sand quartz or the like, which will be compressed by the force of the explosion, thereby completely closing up the apertures in the bottom P. 10 On an explosion wave passing from outside through the nipple N into the cartridge, the first thing to happen is that the heaped material in the cartridge will be compressed. If any hot explosion gases do manage to penetrate 15 through the apertures in the bottom P, they must first find their way therefrom into the narrow ring shaped space between the covering of the cartridge Q and a metal sleeve M which surrounds it concentrically. This 20 external sleeve surface M is however completely surrounded by the cooling substance so that any small portion of the residue of the hot gases that may have found its way through the apertures in the bottom P of the cartridge Q and into the ring-shaped space, will by that time be greatly cooled 25 down, and it is only in this cooled state that it can pass from the upper edge of the ring-space through the closing-sieve T and so reach 30 the interior of the cylinder. On emerging from the sieve T at the upper end of the cartridge these residual explosion gases will strike the metal surface of the container charged with the combustible substance and 35 will thereby undergo a further energetic cooling process.

What is claimed:

1. A safety device for explosive gases or containers of explosive charges, comprising a cartridge shell having a rigid perforated resistable stopper and a filler of loose material such as will not prevent the normal passage of gas from the container in which the cartridge is used, but is adapted to be mechanically compressed by the shock resulting from an explosion and to thereby cut off the passage of the explosion gases to the container, and an outer shell around and spaced from the cartridge shell, so that a narrow space is formed between the two closely arranged surfaces of said shells so that the residue of the hot explosion gases which may pass through the loose material must pass through this narrow space before it can enter the container.

2. Safety device according to claim 1, characterized by the fact that the ring-space surrounds a cartridge constructed in the shape of a tube and containing the heaped substance, so that the hot explosion gases traverse the heaped material within the cartridge in one direction and the ring-space in the opposite direction.

3. Safety device according to claim 1, characterized by the fact that in order to protect the container charged with explosive gases, the latter is fitted with a screw-on nipple together with a tube-shaped extension screwed on to the nipple reaching into the interior of the container and carrying the safety device.
